UNITED STATES PATENT OFFICE.

CHARLES IRVING FULLER, OF ROCHESTER, NEW YORK.

FOLDING MUSIC HOLDER.

1,419,668.

Specification of Letters Patent. Patented June 13, 1922.

Application filed February 19, 1921. Serial No. 446,342.

To all whom it may concern:

Be it known that I, CHARLES I. FULLER, a citizen of the United States, residing at Rochester, in the county of Monroe and State of New York, have invented new and useful Improvements in Folding Music Holders, of which the following is a specification.

This invention has reference to folding music holders and its object is to provide an attachment for a music stand, whereby spare sheets of music or scores may be carried on the stand preparatory to using them as occasion requires.

15 The invention comprises a foldable frame similar to the music holder of an ordinary foldable music stand, and provided with clips adapted to be slipped on the stem of the stand to be held thereon by the elasticity

20 of the clips. The supplemental music holder is in the form of a skeleton pocket adapted to grip the upright stem of the stand between the leg braces and the telescoping member to which the leg braces are attached.

25 The supplemental holder is so constructed that it may be folded up into smaller compass and flattened out to fit into the usual stand case when the latter is folded up, so that both the stand and the supplemental stand are reduced to small compass for transportation with the space occupied by both foldable structures adapted to the capacity of the stand case.

The invention will be best understood 35 from a consideration of the following detailed description taken in connection with the accompanying drawing, forming part of this specification, with the understanding, however, that the invention is not confined 40 to any strict conformity with the showing of the drawing but may be changed and modified so long as such changes and modifications mark no material departure from the salient features of the invention as expressed in the appended claims.

In the drawing:

Fig. 1 is a perspective view of the supplemental music holder in position to be attached to an extended music stand.

50 Fig. 2 is a perspective view of the structure of Fig. 1 in the folded condition.

Fig. 3 is a perspective view of a music stand extended and the supplemental holder also extended and attached thereto.

55 Referring to the drawing, there is shown in Fig. 3 a music stand A comprising an up-

right stem 1 with legs 2 foldable in the usual manner, so that the legs 2 may be extended into tripod form to sustain the stand firmly.

Telescoped into the upper end of the upright 60 1 is an expandable and contractable music holder 3 of customary construction and therefore requiring no special description. As so far described, the music stand need not differ from commercial forms of 65 music stands being of the type in common use and adapted to carry sheets of music or scores, such as are used by bands or orchestras, in holding the music for the individual players.

The legs 2 are provided with braces 4, by 70 means of which the legs may be extended or contracted and held in position. When the legs 2 are extended there is considerable distance between the upper ends of the braces 4 75 and the upper end of the stem 1. This leaves room enough for the attachment of the invention to the stem 1, such attachment being indicated at B in the drawing. The attachment is composed of numerous parts connected for extension or folding. There are provided two channel members 5 in end to end association with the meeting ends of the channel members separately connected by pivots 6 to bars 7 and 7^a respectively and 80 these bars are each individually connected by pivots 8 to strips 9, 10 respectively, the two strips 9 and 10 forming a rectangular frame with the adjacent ends of the strips 9 and 10 connected together by a pivot 11 to 90 other strips 12 and 13 extending to the channel members 5 to which they are connected by other pivots 14. The channels 5 have longitudinal flanges 15 whereby the channel members 5 may be spread into a single 95 trough constituting the bottom portion of the holder and these channel members 5 may be turned on the pivots 6 into face to face relation and thereby folded into small compass. The strips 9 and 10 coact to provide 100 an elongated rectangular frame of about the same spread as the two members 5 together. The various pivots 6, 8, 11 and 14 form flexible junction members permitting the ready folding and extension of the holder with the 105 ease of folding and extension depending upon the tightness of the various pivots which may be regulated as desired.

At the opposite ends of the bar 7^a, there are formed pintle eyes 16 traversed by a 110 pintle or pin 17 in turn traversing one end of a spring clip 18, with the ends of the

clip spread apart away from the pin and constructed in an elastic manner so as to be readily snapped over the stem 1 of the music stand with sufficient grip thereon to hold 5 the container to the stand and yet permit its ready removal from the stand.

The frame made up of the strips 9 and 10, 12 and 13 and the channels 5 with their flanges 15 constitute a holder of suitable 10 size to contain numerous music scores in accessible position and from which container the scores may be readily chosen and removed. The extra music is thereby held in an out-of-the-way position, from which position the scores may be readily removed as needed and into which holder they may 15 be replaced after use. There is no liability of loss of the scores by reason of wind blowing them or the scores being knocked from 20 the stand where the additional supply of scores is stored.

The clips 18 are stiffly hinged to the bar 7^a, with the hinge moving with sufficient friction to hold the storage frame from accidental movement but still the hinge is sufficiently flexible to permit folding of the clip 25 flat against the bar 7^a for storage purposes.

What is claimed is:—

1. A folding music holder for attachment 30 to and removal from a music stand; comprising channel members at the bottom, spaced upright bars separably and pivotally connecting the channel members at their meet-

ing ends, horizontal strips forming a rectangular frame at the top and pivoted to 35 each other, said strips being pivotally connected to said bars, and vertical strips pivotally connecting the horizontal strips to said channel members at their outer ends.

2. A folding music holder comprising a 40 pair of horizontally disposed channel members arranged end to end, a pair of upright bars pivotally connected at their lower ends to each of the channel members, a pair of horizontal strips forming a rectangular 45 frame pivotally connected to the upper ends of the vertical bars, and a pair of strips pivotally connected to the horizontal strips at their upper ends and to the outer ends of the channel members at their lower ends, 50 and attaching clips connected to one of the upright bars for attaching the holder to the upright stem or post of the music stand.

3. In combination with a music stand, a foldable music holder for attachment to and removal from the music stand, said holder having a substantially rectangular frame at the top, and a channel member at the bottom, said frame and said channel member being connected together by pivoted strips 60 or bars, and pivoted clips carried by the holder to engage over the upright stem or post of the music stand.

In testimony, that I claim the foregoing as my own, I have hereto affixed my signature. 65

CHARLES IRVING FULLER.
